UNITED STATES PATENT OFFICE.

CHARLES E. McMANUS, OF NEW YORK, N. Y.

BOTTLE CAP AND THE METHOD OF MAKING SAME.

Application filed May 28, 1921. Serial No. 473,428.

To all whom it may concern:

Be it known that I, CHARLES E. McMANUS, a citizen of the United States, residing at the borough of Manhattan, in the city, 5 county, and State of New York, have invented certain new and useful Improvements in Bottle Caps and the Methods of Making Same, of which the following is a specification, reference being had, therein 10 to the accompanying drawings, which form a part thereof.

My invention relates to bottle caps and the method of making same, and more particularly to a cap consisting of a metallic 15 shell having a skirt by means of which it is attached to the neck of a bottle, and a cushion disk within and cemented to the shell and adapted to be seated against the top of the neck of a bottle to make a gas 20 and liquid tight joint.

Heretofore it has been the common practice in this art to employ a metallic shell having a fluted skirt and a cylindrical portion within which a cushion disk usually 25 made of cork, or of what is known as "cork composition", has a close fit, one face of the disk being bonded to the inner top of a shell by means of a suitable cement applied directly to the shell and to the disk, or by 30 means of a paper collet coated on both sides with the cementing compound. In applying the cement directly to the shell, it has been the alternative practice to "spot" the sheets of tin from which the shells are made 35 with this cement, or to apply the cement to the shell while it is passing through the assembling machine.

It has also been a common practice to coat the entire surface of the cushion disk 40 with paraffin, to close the surface voids, and to ensure the impermeability of the disk. The use of paraffin necessitates the employment of a special cementing compound, and in a measure interferes with that permanent 45 bond between the shell and the disk which is desirable as preventing the separation of these members when applying the cap to a bottle, particularly with manually operative capping machines.

With the above prior art conditions in 50 mind, I have produced a closure cap wherein the exposed surface only of the disk is provided with a superficial coating of a finishing wax compound, thus not only ensuring 55 the desired impermeability of the disk to gas

and liquid from the bottle contents, but permitting the production of caps wherein the disks will be uniformly and firmly bonded to the shell. The time interval required for the assembling of a cap embodying my 60 invention is also much reduced as a result of the facility with which the untreated surface of the disk may be bonded to the shell. Furthermore, the surfacing compound may be applied to the exposed surface of the disk 65 with regard only to the quantity thereof required to impart the desired finish to this surface and to close any voids which might lead to the presence of leakers in bottles to which the caps are applied, the destruction 70 of the film of wax upon the surface of the disk adjacent the inner top of the shell in bonding the disk thereto, requiring no consideration.

The method I employ in assembling caps 75 embodying my invention eliminates the step of paraffining the disks, which has heretofore been common in the art, and other steps for ensuring the proper distribution of the paraffin about the surface of the disk. The 80 method I employ also ensures substantial uniformity in the finish of all disks.

The invention consists primarily in a bottle cap embodying therein a skirted metallic shell, a cushion disk, a binding stratum between said disk and the inner top of said shell, and a stratum of an innocuous surfacing compound impermeable by the gas and liquid contents of a bottle, applied only to the exposed surface of said disk, and to such 90 other novel characteristics, and to the novel method of producing said cap, all as hereinafter set forth and described, and more particularly pointed out in the claims hereto appended. 95

Referring to the drawings,

Fig. 1 is a section through an ordinary metallic shell as commonly used in the production of closure caps;

Fig. 2 is a sectional view through a composition cork disk adapted to be assembled in the shell; 100

Fig. 3 is a cross sectional view of the completely assembled and finished cap; and

Fig. 4 is a diagrammatic view illustrating the method of assembling the cap. 105

Like letters refer to like parts throughout the several views.

In the embodiment of my invention shown in the drawings, the shell α is shown as 110

being of the ordinary fluted skirt type extensively used for closure caps for bottles, although it is not my intention to limit the invention to the use of shells of this particular type. The portion of the shell adjacent the top a' thereof is cylindrical as shown at a^2 , the top a' itself being of concave-convex form as is usual with such shells.

The cushion disk b is the usual cork disk and may be produced either from natural cork or from granular cork, the granules of which have a thin surface coating of a binding material which is capable of being vulcanized or cured at an elevated temperature, and when so vulcanized or cured has all of the properties as to acid resisting properties, elasticity, etc., as soft vulcanized rubber. Whether a natural cork disk or a composition cork disk be used, the disks will have in common the characteristic that when assembled in the cap, the disk as a whole will have no surface coating of any kind, thus causing substantially the entire area of the surface thereof presented toward the inner top of the shell a to be a clean dry natural cork surface, since the volume of binder about each granule of cork is sufficiently thin to cause no material reduction in the area of the cork presented toward the shell when composition cork is used.

Between the surface of the disk b and the inner surface of the top a' of the shell is a stratum of any suitable binding material or cement, indicated at c in the drawings, by means of which said disk is firmly bonded to the inner top of the shell a so as to resist displacement of the cork disk while the cap is being applied to a bottle. The stratum c of adhesive is very thin, its thickness being exaggerated in the drawings.

The employment of a disk cemented to the shell in the manner described is common to all closure caps of this type now and heretofore used, and consequently I make no claim of invention of this characteristic of the cap considered alone.

The disk b has upon the exposed surface thereof, a thin stratum of a finishing wax compound d which has the two-fold effect of closing any voids or pores in this surface of the disk so as to make it impermeable by the gas and liquid contents of a bottle to which the cap is applied, and giving a neat, smooth finish to the disk. Any desired suitable wax may be used for forming the stratum d , a cerasine wax composition being preferably used, which composition has included therein a bleaching agent, which will act to brighten the cork beneath the surface stratum, this stratum excluding air from the exposed surface of the disk so as to always keep this surface clean, and protect it against discoloration from oxidation.

It is essential that the stratum d be limited to the exposed surface of the disk b

since if the surface of the disk adjacent the top a' be so coated, there is always likelihood of an improper bond between the disk and the shell, as in articles the cost of which is but a fraction of a cent, careful inspection to detect defective caps is impracticable, and a large number of defective caps would make the cost of production excessive.

In producing caps embodying my invention, I employ a novel method by which the stratum d may be applied to the cork disk without additional steps in the process of making the cap, and not requiring any additional handling thereof as compared with the present methods of producing such caps. In fact by the method of my invention, I am enabled to eliminate that handling of the disks b incidental to coating same with paraffin in the manner heretofore employed.

As heretofore stated, the manner of applying the adhesive or cement to the inner surface of the top a' of the shell a is that which has heretofore been practiced, and the character of this cement is immaterial to the invention, it being possible to use the cements which have long been in use heretofore, having either a resinous, a casein or an albuminous base combined with other ingredients to facilitate the handling of the cement and the rapid hardening thereof. The cement may be applied by spotting the sheets of tin before the shell is formed by a punch press, by being applied to the inner surface of the top a' in liquid form, while passing through the assembling machine, or by being applied thereto through the medium of a paper collet coated therewith. For the purposes of my method it is merely essential that the shell shall have applied thereto a suitable adhesive or cement prior to the introduction of the cork disk thereinto.

In the diagrammatic showing of Fig. 4, I have illustrated the method as including applying liquid cement to the shell while it is passing through the assembling machine.

After the cement has been thus applied, the cork disk b is delivered to the shell upon the cement contained therein, and thereafter a wax composition is sprayed or dropped upon the exposed surface of the cork disk, the stratum d being formed of this composition.

After the wax composition has been applied to the disk b , the shell a and its contained disk is simultaneously subjected to heat and pressure with the two-fold result that the wax composition is melted and thoroughly diffused about the exposed surface of the disk b and flowed into any voids or interstices adjacent this surface, and the cement or adhesive is so conditioned as to secure a firm binding of the disk and the inner top of the shell. The shell a and its disk b are subjected to a continuous heat

and pressure for a sufficient interval to secure the results above referred to, after which the shell is exposed to atmosphere, or to some other cooling medium, so as to firmly set the adhesive or cement and harden the composition wax surfaces.

The method of my invention may be practiced in the ordinary bottle cap assembling machine, requiring merely the addition of 10 the mechanism for applying the wax composition to the cork intermediate the point of delivery of the disk to the shell and the finishing head, wherein heat and pressure are applied thereto.

15 In this manner additional handling of the disk or the cap and additional steps in assembling and finishing same are avoided and the application of the finishing surface does not in any way prolong the time required to 20 completely assemble and finish a cap, since the wax composition will be applied to the disk of one cap while the preceding operation of delivering the cork to a shell is being effected by another mechanism.

25 It is not my intention to claim broadly the application of a finishing wax surface to cork disks used in closure caps, but I believe it to be broadly new to provide a cap in which only the exposed surface thereof is so 30 coated, and to provide a method whereby this coating may be applied without any additional handling of the cap.

These characteristics of my invention are 35 of considerable importance, since they permit the use of cork disks without intermediate handling and in the condition in which they are produced by the cutting or the slicing machines according to whether the disks are formed from sheets or from rods, and have a surface upon which the cementing medium will readily act in binding the disk to the shell.

Having described the invention, what I 45 claim as new and desire to have protected by Letters Patent, is:—

1. A bottle cap embodying therein a skirted metallic shell, a cushion disk of substantially the same diameter as, and covering 50 the entire inner surface of, the top of said shell, whereby a portion of said disk adjacent the edge thereof is adapted to seal against the top of a bottle, and the central portion thereof protects the metal of the shell from the contents of the bottle, a binding stratum between said disk and the inner top of said shell, and a stratum of an innocuous surfacing compound impermeable by the 55 gas and liquid contents of a bottle, applied only to the exposed surface of said disk.

2. A bottle cap embodying therein a skirted metallic shell, a cushion disk, a binding stratum between said disk and the inner top

of said shell, and a surface coating of wax applied only to the exposed surface of said 65 disk.

3. A bottle cap embodying therein a skirted metallic shell, a cushion disk, a binding stratum between said disk and the inner top 70 of said shell, and a surface coating of wax and a bleaching medium, applied only to the exposed surface of said disk.

4. The herein described method of making bottle caps consisting in delivering a cushion disk to a skirted metallic shell having a cement or adhesive in the inner top thereof, 75 applying wax to the exposed surface of said disk and thereafter applying heat at an elevated temperature and pressure to the disk and the shell to simultaneously bond the 80 disk to the shell and diffuse the wax about the entire exposed surface of the disk.

5. The herein described method of making bottle caps consisting in delivering a cushion disk to a skirted metallic shell having a cement or adhesive in the inner top thereof, 85 applying wax to the exposed surface of said disk, thereafter applying heat at an elevated temperature and pressure to the disk and the shell to simultaneously bond the disk to the shell and diffuse the wax about the entire exposed surface of the disk, and thereafter 90 subjecting the caps to a lower temperature to harden the cement or adhesive and the wax.

6. The herein described method of making bottle caps consisting of successively delivering a cement to a skirted metallic shell, delivering a cushion disk to the shell, applying wax to the exposed surface of said disk 100 and thereafter applying heat at an elevated temperature and pressure to the disk and the shell to simultaneously bond the disk to the shell and diffuse the wax about the entire exposed surface of the disk.

7. The herein described method of making bottle caps consisting of successively delivering a cement to a skirted metallic shell, delivering a cushion disk to the shell, applying wax to the exposed surface of said disk, thereafter applying heat at an elevated temperature and pressure to the disk and the shell to simultaneously bond the disk to the shell and diffuse the wax about the entire 115 exposed surface of the disk, and thereafter subjecting the caps to a lower temperature to harden the cement or adhesive and the wax.

In witness whereof I have hereunto affixed my signature, in the presence of two subscribing witnesses, this 18th day of May, 1921.

CHARLES E. McMANUS.
